UNITED STATES PATENT OFFICE.

JOHN F. COOLEY, OF NEW YORK, N. Y.

AVIATION APPARATUS.

1,084,198.

Specification of Letters Patent. Patented Jan. 13, 1914.

Application filed February 2, 1910. Serial No. 541,457.

To all whom it may concern:

Be it known that I, JOHN F. COOLEY, a citizen of the United States, residing in the city of New York, county of New York, 5 and State of New York, have invented certain new and useful Improvements in Aviation Apparatus, of which the following is a specification.

My invention relates to navigation of the 10 air by aviation or aerodynamic apparatus as distinguished from aerostatic or balloon-like apparatus.

The aviation apparatus in which I have embodied my invention is of the so-called 15 "aeroplane" type, although this does not preclude the employment in some way therein of the principle of the helicopter or that of the ornithopter. Being a so-called aeroplane the herein described form of my invention has laterally-outspread supporting 20 surfaces which may be either curved or plane, and which depend for their action on the aerocraft having speed, whether produced by the action of gliding down by the 25 force of gravity, or by a mechanical propeller, or otherwise, the sustaining quality being attained by attacking the air more or less obliquely, the supporting surfaces being inclined to the horizon. In such an apparatus, whether a mere "glider" or otherwise, 30 certain desiderata are recognized, and if the craft is self-propelled, further characteristics or qualities are desirable or necessary, to render it practical. Indeed while 35 air navigation is one of the oldest of questions, it is fraught with difficulties and dangers and presents many problems hitherto not satisfactorily solved. For example, among the problems are: the fore-and-aft, 40 balance and its proper control, not only to prevent the craft being diverted upward or downward, with possible calamitous results, but to enable it to be guided in upward or downward direction at will. The steering to 45 right or left in a simple, effectual and balance-preserving manner. Increase of lateral stability or balance by having a design less affected by disturbing influences, or entirely obviating need of balancing apparatus. The increase of speed by having a design that more readily penetrates the air and avoids excessive friction without sacrificing 50

its supporting qualities; thus enabling a stated power to give more effect. The increase of speed by increasing lineal dimensions and areas thereby enabling motors to be used giving greater proportionate driving power than possible with smaller craft. This desideratum is advanced by having a design and frame construction of increased 55 economy of weight. Each advantage of such nature is of high importance, for each helps increase speed, which in turn increases the sustaining power of the surfaces, and again permits increase of 60 strength in all parts of the craft and its propelling mechanism. Prevention of breakage by increase of strength of parts and otherwise is one of the greatest essentials. It has been thought the sustaining 65 surface must be small or limited in size since the weight of parts theoretically increases out of proportion thereto, but I have discovered by calculation that with a proper design and construction, such as that herein, this is untrue, and that any disproportionate weight-increase is practically offset by the greater sustaining effect; for quadrupling the supporting surface, and the sustaining effect will be more than quadrupled, 70 and the volume of underlying compressed air will be practically octupled. Again, the added speed of progression possible in a larger craft from using a larger motor obviates any loss of efficacy. 75

To the attainment of the above and other objects my improvements are directed, and as examples of the many ways to employ the principles of the invention, I have illustrated and will hereinafter describe some 80 embodiments thereof, the novel and characteristic qualities and features of which will be at the end set forth in the claims.

In the accompanying drawings forming a part hereof, Figures 1 to 4 inclusive illustrate a simple form embodying some of the main principles of my improvements; Fig. 1 being a side elevation, Fig. 2 a top view, and Figs. 3 and 4 similar rear views with the parts in different adjustments. Figs. 5 100 and 6 illustrate another form embodying also the main principles and further important details; Fig. 5 being a side elevation and Fig. 6 a rear view. The preferred em- 85

bodiment of my improvements is shown in Figs. 7 to 14 inclusive, in which Fig. 7 is a general perspective view, Fig. 8 is a side elevation, Fig. 9 a top view, Fig. 10 a rear elevation, Fig. 11 an enlarged side view of details at the rear. Fig. 12 is a diagrammatic rear view of the three surfaces (two wings and keel) and their controlling cables. Fig. 13 is a similar view showing different adjustments. Fig. 14 is a detail view showing parts of the three surfaces and illustrating the cable connections for controlling the surfaces from a controlling lever or tiller.

15 Similar letters of reference designate corresponding parts in the several figures of the drawings.

Referring first for convenience to Figs. 1 to 4 showing in a conventional manner a simple form of supporting unit, it will be seen that this is capable of having its outspread supporting surfaces concaved at will for the purpose of regulating fore-and-aft balance or upward and downward steering; 25 either the forward or rear portion of the supporting surface being deflected upwardly or downwardly with relation to the remainder. A wire α' extending from the bow at the left to the stern at the right can be more or less tightened or loosened, for example by means of a turn-buckle α^2 . The tighter the wire is stretched, the more concave will the supporting surface become.

As seen the apparatus is of a form having a central structure or spine B and an outspread supporting surface comprising a plurality of air-resisting surfaces A, one being shown on either side. When the wire α' is tightened these two surfaces or wings are 40 pulled downwardly at one or both ends with respect to the apparatus as a whole. This can be done as shown by deflecting the spine itself, that is either by flexing it or swinging it by means of a joint or hinge if preferred.

In the form shown in Figs. 1 to 4 the right and left steering is done by ropes α^3 passing from the wings to the spine rear, and to the point α , the aviator sitting at α having control of the turn-buckle α^2 and ropes α^3 . On pulling one rope α^3 and slackening the other, the spine is deflected at its rear end to one side, e. g., the right as in Fig. 4, which so changes the wing curvature and wind pressure as to compel 55 the craft to turn to the right. No propeller is shown on this form, as a propeller may be omitted in the case either of a glider or an apparatus to be towed.

Passing now to the form in Figs. 5 and 6, shown also in a more or less conventional way, further features of my invention may be referred to. Thus besides the pair of wings A, is provided a keel C, shown as single in construction and arranged vertically

in the center, preferably beneath the spine. 65 This keel may be considered as a substructure forming a point of vantage whence to pull the wings and spine downwardly for regulating the concavity of the apparatus. Thus ropes α pass from the wings and keel 70 around the rear end of the spine and forwardly to the aviator, whereby he can by pulling the proper rope, cause the spine to be flexed or swung downwardly, thus lowering the rear portions of the two wing surfaces, dotted lines being employed to indicate the lowered position of spine and wings.

The general shape or design of my apparatus is such as to give great lateral stability 80 or balance as against disturbing influences, also to more readily penetrate the air without sacrificing supporting qualities, also to permit a frame construction of such economy and weight as to permit increase of dimension and of supporting area with the advantages already hereinabove recited. The shape or design may be said to be that of a triangle or other simple polygon multiplied as desired about a central structure or 90 spine, the long sides coinciding with or contiguous to the spine. Such construction permits the use of a simple strut-and-stay truss, which substantially constitutes the entire frame. The several polygons being alike 95 and opposed, give the effect of a surface which is symmetrical, and when only two wings are employed, both triangular, the result is a quadrilateral form pointed at both ends. This design and structure being not 100 only light as described, further possesses the quality of stability, which is enhanced by slanting the two wings upward away from each other; and by shifting the location of the cross-struts or braces b to a point near 105 the stern, the apparatus as a whole is given a sharp dart-like bow which assists greatly in the penetration of the air at high speeds, and minimizing friction.

In the form of Figs. 5 and 6 there are 110 three triangular surfaces substantially alike, the third one constituting the keel C, which for convenience is shown single in construction though it might be constituted of a pair of surfaces. It will be seen that the keel is 115 not only like the two wings in shape and structure, but it is also like them in having its rear part laterally movable, this being for the purpose of guiding the craft to left or right, the deflecting portion of the keel 120 serving in the place of an independent rudder. As explained three ropes α pass from the wings and keel around the rear end of the spine and forward to the aviator who may so manipulate the ropes as to cause any 125 desired deflection either of the wings or the keel. This form of machine is shown to possess a driving motor M located generally

near the center of balance of the supporting surfaces, and a propeller N located at the front end of the apparatus; also front and rear landing wheels D, D'.

5 The importance of the regulation of the fore-and-aft curvature or concavity is great, for were the curve a fixed one, as is usual, it would render the craft a one-speed craft, or at least limited in its range of speed. The 10 explanation is that for a given speed, say 40 miles per hour, a certain degree of curvature of the supporting surfaces will be effective, it being made of such pitch as to keep up a supporting air pressure from bow to stern; 15 whereas for a different speed such pitch would no longer be effective. For example were speed increased to 100 miles the effective pitch should be greatly decreased, the curve becoming flatter, and enabling the 20 craft running at a given altitude to easily keep on a level keel, whereas the more pronounced curve with the high speed would produce a constant tendency for the craft to steer downward and dive. This principle of 25 fore-and-aft curve or concavity regulation I desire to protect irrespective of the type of craft. The principle also operates when the craft is to run at constant speed but at different altitudes. At the same time, the 30 mechanism illustrated serves, as previously stated, for varying the upward and downward angle of advance of the craft.

The principle of having a central member or spine around which are arranged at, 35 roughly speaking, equal or comparable angles, three or more surfaces, is important. The lower surface may be a keel, and it not only affords support when turning, and tends generally to steady the craft, but is 40 capable of becoming a supporting surface, if the craft should possibly tilt too far. An equalizing effect is thus produced which practically renders the craft non-capsizable.

The principle of assembled polygons of a 45 form enabled by the strut-and-stay truss construction insures not only a pointed bow with an inclined stay to cut the wind, but also a pointed stern; which in turn renders possible the valuable controlling mechanism 50 to be described. It also constitutes of the craft one which, in case of need, may reverse or back up in mid-air, if the propeller be reversible.

The truss referred to is substantially flat, 55 by which I mean it is in one plane, as distinguished from having three dimensions, although of course the truss and the surface covering it may be slightly curved or concaved as stated. The bulging of the fabric or air-resisting material, and the give of the 60 stay wires under the pressure of the wind cause a substantially continuous curve is the supporting surface from bow to stern. The use of opposed trusses about a spine braces

the latter, which substantially forms a 65 stringer to each truss. The fabric covering stiffens the truss and in effect forms a continuous bracing therefor.

Coming now to the preferred embodiment shown in Figs. 7 to 14, this, it should be first stated, is of a multiple form. By multiple I mean that there are a plurality of units, some and preferably all of which would have some or all of the features of my improvements; and the number and inter-relation of the different units may of course be indefinitely varied. Units may be arranged side by side or in the form of a bi-plane or tri-plane, etc., either with parallel or crossed surfaces; the connections between 70 the units may be rigid or flexible; or all these different features may be combined. The multiple unit apparatus of Fig. 7, etc., is of a tandem formation with a main or rear unit and in front of it a smaller or supplemental unit rigidly secured to the main unit and having a generally similar shape and construction though not possessing all the details as to manipulation.

Coming now to the form and construction 90 of the main unit of Figs. 7 to 14, it is to be understood that this embodies the various qualities and features previously herein discussed, and which will not be repeated as the following description is merely of one 95 specific form of embodiment of the broad principles which I desire to cover by Letters Patent. On either side of the center line are the two supporting surfaces or wings A', A'' and beneath them is the keel structure C. 100 The extreme rear portions of the wing and keel surfaces are marked respectively a', a'' and c'. Along the center line of the apparatus is a structure which may be termed a central member or spine, which is of the 105 entire length of the apparatus, although different portions of the central member are differently constructed. For example, for the major portion of the length of the apparatus the central member is for convenience combined or consolidated with a car so that either the car or a portion thereof may be considered as constituting a part of the spine. The car may also be considered as combined with the keel since it is covered 110 with air-resisting material on both sides, and thereby in effect constitutes a hollow keel. The car is a built up framework made from any suitable material and preferably having a narrow cross section, the same 115 tapering to a point both above and below and toward the bow and stern. A number of vertical pieces e are shown arranged in substantially parallel planes, these being extended above the actual line of the spine and 120 meeting at points e', which points are connected by a longitudinal member e'' extending fore and aft. The parallel vertical sec-

tions e are also shown as converging to points e' at their lower ends. All these described members constitute a sort of framework connected by longitudinal member E' for the apparatus as well as providing the necessary car space for a motor M shown as resting upon a platform e^4 within the car, and seats e^5 for the aviator and a passenger. This structure just described extends from 10 the bow rearward to the point E , and the continuation of the spine beyond that point may be of a different nature, for example a simple spar such, for example, as the swinging spar or boom F , whose rear extremity 15 forms the extreme stern of the apparatus. It will be seen that either flexing or swinging the boom F out of a position in perfect alinement with the rest of the apparatus will serve to vary or deflect the line of the so-called central member or spine of the apparatus. Coming now to the keel, this comprises an air-resisting fabric or material shown at C' and covering the interior substructure beneath the spine on both sides 25 thereof, so that the keel is in effect a double or hollow keel with space between its two surfaces to receive the interior structure and car. The keel surface extends from the bow to the extreme stern of the main unit and 30 although bulged where the material is doubled, it is desirable to maintain the keel surface substantially continuous from bow to stern. The extreme stern portion to the rear of the point E is marked c' and the 35 propeller may conveniently be located within a space cut out of the keel surface just forward of this portion c' . Rather than cut away the fabric forming the keel surface at the point where the aviator sits, I prefer 40 to constitute it partly of a celluloid or other transparent sheet which, it will be seen from Fig. 10, is bound to take an inclined position so that the aviator is able to see not only forward but downward; and any further 45 vision for increasing the aviator's scope of vision may be adopted. G represents the propeller which with the motor M constitutes a convenient form of propelling mechanism for an apparatus of the character herein described. The propeller shaft g is shown as extending in an inclined direction from the motor down to the propeller, and its bearings may be arranged in an obvious way. D represents a front, and D' 55 two rear landing wheels which may be bicycle wheels, although any other form of landing device might be substituted; and under favorable circumstances these wheels will serve also for supporting the apparatus 60 as it runs along the ground when being launched. It will be understood that exterior stays or wires may be applied at various points in order to preserve the proper relative positions between the wings and

keel, although for the sake of clearness in 65 the drawings I have omitted showing such stays. As already premised the regulation of the craft is performed by controlling the curvature or concavity of the several surfaces, namely the two supporting surfaces 70 or wings A' and A^2 and the substantially vertical surface or keel C' . This is effected by the proper movements of the respective rear portions a' , a^2 and c' of said three surfaces. For the purposes of the diagrammatic illustrations, I have applied the letters P , Q and 75 R to the extreme rear points of the surface portions a' , a^2 and c' respectively; and the cables or stay wires which join these three surfaces to the rear of the boom F are correspondingly marked p , q and r , the rear 80 end of the boom itself being designated S . As seen in Fig. 11, the boom F is mounted at its forward end to a universal joint F' enabling the boom to be swung in any desired direction whether upward, downward, to right, to left and at various angles. The rear end of the boom is provided with three pulleys s , through each of which passes one of the three cables p , q and r , said cables 85 then passing forward toward the aviator as shown. In order to permit the boom F to swing as described, each of the rear surfaces a' , a^2 and c' is so designed as to leave a substantial space between it and the boom so 90 that there will be a substantial length of cable p , q and r between the respective points P , Q and R , and the pulleys.

From the above description it will be seen that the position of the boom can be controlled by the manipulation of the cables p , q , r , since upon pulling one of said cables and slackening the other two the boom is bound to draw toward the point P , Q or R which corresponds to the cable pulled. Referring now to Fig. 12, the full lines show 100 the normal positions of the rear surface portions a' , a^2 and c' , and of the points thereof P , Q and R , and of the end S of the boom. If now the cables p and r should be pulled 105 by the aviator and the cable q slackened, the end S of the boom will be swung downwardly to the right, for example to the position S' , and the two surfaces a' and c' will take the dotted positions shown with their 110 points P and R shifted to the new positions P' and R' . In this position the rear surface c' of the keel being deflected to the right will act as a rudder to steer the craft to the right. The action of the wind pressure upon the 115 surface c' under these conditions would have a tendency to tip the craft or rotate it about its spine in the direction of the hands of a watch; but it will be seen that the downwardly deflected rear portion a' of wing A' will have an exactly counterbalancing effect 120 so that the craft while responding to the desire to turn toward the right, will main-

tain its equilibrium. For upward and downward steering or for the regulation of the fore-and-aft curvature of the supporting surfaces, irrespective of the keel movements, 5 the latter may be kept stationary and the rear portions a' and a^2 of the wings raised or lowered as necessary. For example in Fig. 13 in which the dotted lines show the normal positions of the parts, the cable r 10 has been pulled and the cables p and q have been slackened. The result is that the extremity S of the boom has dropped from its normal position S to a lowered position S^2 , pulling down with it the points P and Q of the wing surfaces; so that both of the rear 15 wing-surface portions a' , a^2 have been deflected downwardly so as to give a curvature or increase the curvature or concavity of the supporting surfaces for whatever purpose this may be desired, whether to attain 20 a different rate of speed, a different upward or downward incline of advance, or otherwise.

Instead of merely giving the aviator the 25 ends of the three ropes p , q and r for manipulation, these may be in some way connected to a tiller device such as a wheel or lever, by which the aviator is enabled to automatically control all three surfaces in 30 unison and in co-operation. For example referring to Fig. 14, the three ropes p , q , r are shown passing forwardly and around three pulleys p' , q' and r' , and from thence to the extremity of a lever or tiller T . This 35 tiller has its forward arm with a handle t and a rearward arm t' to which the different cables are attached, and the pivot t^2 is supposed to be fixed upon the car or its framework. The handle t of the tiller can 40 be thrown upward or downward or to the right or to the left and will produce a corresponding movement in the position of the boom F . For example if the tiller is thrown upward to the dotted position t^3 45 then the rear arm t' of the tiller will be lowered, which will pull upon and shorten the cable r , at the same time slackening the cables p and q . As already explained this will effect the lowering of the boom, for example 50 to the position shown in Fig. 13.

What I claim as new and desire to secure by Letters Patent is:

1. In an aviation apparatus, a supporting unit having on either side of its center line 55 an outspread supporting surface, a keel member therebelow, and means extending from or connected to said keel for at will deflecting the rear portions of said supporting surfaces in upward and downward directions for changing the fore-and-aft concavity thereof.

2. In an aviation apparatus, a supporting unit having a central member or spine, and on either side of its center line an outspread

supporting surface, a keel member therebelow, and means extending from or connected to said keel for at will deflecting the rear portions of said spine and supporting surfaces in upward and downward directions for changing the fore-and-aft concavity thereof.

3. In an aviation apparatus, a supporting unit having a central member or spine, and on either side of its center line an outspread and upslanted supporting surface, a keel member therebelow, and means extending from or connected to said keel for at will deflecting the rear portions of said spine and supporting surfaces in upward and downward directions for changing the fore-and-aft concavity thereof; said rear portions of spine and surfaces being capable of relative separation when lowered.

4. In an aviation apparatus, a supporting unit comprising a central member or spine, and a plurality of surfaces each made up of a substantially flat strut-and-stay truss covered with air-resisting material and with the spine forming the truss stringer or base, combined with means for at will deflecting portions of the said surfaces for changing the fore-and-aft concavity thereof.

5. In an aviation apparatus, a supporting unit comprising a central member or spine, and a plurality of surfaces each made up of a substantially flat strut-and-stay truss covered with air-resisting material and with the spine forming the truss stringer or base, combined with means for at will deflecting portions of the said surfaces for changing the fore-and-aft concavity thereof; and a structure or keel of substantial depth or height to which extends or is connected the said deflecting means.

6. In an aviation apparatus, a supporting unit comprising a central member or spine, and a plurality of surfaces each made up of a substantially flat strut-and-stay truss covered with air-resisting material and with the spine forming the truss stringer or base, combined with means for at will deflecting an end of the spine and thereby deflecting portions of the said surfaces for changing the fore-and-aft concavity thereof.

7. In an aviation apparatus, a supporting unit comprising a central member or spine and a plurality of polygonal supporting surfaces, more or less opposed to each other about said spine, their bases contiguous to the spine, combined with means for at will deflecting portions of each of said surfaces for changing the fore-and-aft concavity thereof.

8. In an aviation apparatus, a supporting unit comprising a central member or spine and a plurality of polygonal supporting surfaces, more or less opposed to each other about said spine, their bases contiguous to

- the spine, combined with means for at will deflecting an end of the spine and thereby deflecting portions of each of said surfaces for changing the fore-and-aft concavity 5 thereof.
9. In an aviation apparatus, a supporting unit having a central member or spine and a symmetrical quadrilateral supporting surface, the latter comprising a pair of out-spread supporting wings each of substantially triangular shape with the longer side of the triangle contiguous to said spine, whereby said supporting surface as a whole is substantially pointed at the bow end; combined with means for at will deflecting an end of the spine and thereby deflecting portions of said wings for changing or regulating the fore-and-aft concavity thereof.
10. In an aviation apparatus, a supporting unit having a central member or spine, an outspread supporting surface, and a substantially vertical surface or keel, said keel having a polygonal shape with the base of the polygon along said spine, combined with 20 means for at will deflecting one portion of said keel relatively to the remainder for steering to right and left, the deflecting portion of said keel forming substantially a rear continuation of the main surface of the keel.
11. In an aviation apparatus, a supporting unit having at least three surfaces arranged around a central member or spine, combined with means for at will deflecting one portion of each of any two or more of 25 said surfaces for regulating the concavity thereof.
12. In an aviation apparatus, a supporting unit comprising outspread supporting surfaces and a substantially vertical keel surface, combined with means for at will deflecting one portion of each of said supporting surfaces and said keel surface for cooperatively regulating the concavity of 30 said several surfaces, substantially for the purposes described.
13. In an aviation apparatus, a supporting unit comprising outspread supporting surfaces and a substantially vertical keel surface, combined with means for at will 35 angularly deflecting any two of said surfaces toward or from each other, substantially for the purposes described.
14. In an aviation apparatus, a supporting unit comprising a central member or spine, the rear portion of which is capable of being flexed or swung to positions at any desired angle to normal position, combined with three or more surfaces arranged about 40 said spine and capable of having their rear parts deflected, and means whereby said spine rear may be moved and said surfaces thereby controlled.
15. In an aviation apparatus, a supporting unit comprising a central member or 45
- spine, the rear portion of which is capable of being flexed or swung to positions at any desired angle to normal position, combined with three or more surfaces arranged about said spine and capable of having their rear parts deflected, and means whereby said spine rear may be moved and said surfaces thereby controlled, said means comprising cables or the like from the rear of each surface to the rear extremity of the spine, and mechanism for tightening and loosening the several cables in harmony for causing the spine movements and surface deflections.
16. In an aviation apparatus, a supporting unit comprising a central member or spine, the rear portion of which is capable of being flexed or swung to positions at any desired angle to normal position, combined with three or more surfaces arranged about said spine and capable of having their rear parts deflected, and means whereby said spine rear may be moved and said surfaces thereby controlled, said means comprising cables or the like from the rear of each surface to the rear extremity of the spine, and mechanism including a tiller with connections for tightening and loosening the several cables in harmony for causing the spine movements and surface deflections.
17. In an aviation apparatus, a supporting unit comprising a central member or spine and at least three surfaces, arranged in more or less mutual opposition about said member, each surface consisting of a substantially flat strut-and-stay truss covered with air-resisting material, and said central member forming the base of said trusses; said spine at its rear being capable of flexure or swinging and provided with mechanism for at will moving it and thereby controlling the concavity of said several surfaces.
18. In an aviation apparatus, a supporting unit comprising a central member or spine and at least three surfaces, arranged in more or less mutual opposition about said member, each surface consisting of a substantially flat strut-and-stay truss covered with air-resisting material, and said central member forming the base of said trusses; said spine at its rear being capable of flexure or swinging and provided with mechanism for at will moving it and thereby controlling the concavity of said several surfaces, such mechanism including cables extending from said surfaces to the spine rear and to a tiller device for controlling the several cables, spine and surfaces.
19. In an aviation apparatus, the combination of at least two supporting units connected together, each having on either side of its center line an outspread supporting surface, a keel member therebelow, and means extending from or connected to said keel for at will deflecting the rear portions

of said supporting surfaces in upward and downward directions for changing the fore-and-aft concavity thereof.

20. In an aviation apparatus the combination of at least two supporting units connected together rigidly in tandem formation, each having a central member or spine and an outspread supporting surface on either side, together with means for at will

deflecting a portion of at least two of said surfaces relatively to the remainder, for changing the fore-and-aft concavity thereof.

In witness whereof I have hereunto set my hand, this 1st day of February, 1910.

JOHN F. COOLEY.

Witnesses:

CONRAD A. DIETERICH,

ELIZABETH B. KING.
